SPRING

Joseph N. Weil, East Orange, N. J.

Application April 21, 1943, Serial No. 483,961

5 Claims. (Cl. 155—179)

My invention relates to a spring or springs adapted for use in furniture, such as sofas, chairs, beds, box springs, automobile seats, and the like.

Heretofore, to secure spring action in furniture, day beds and the like where such spring action is desired, it has been customary to use metal coil springs secured to the bottom of the article of furniture by webbing of burlap and the like. Because of the present war metal coil springs cannot be used for this purpose and, moreover, the proper webbing is very difficult to obtain.

It is an object of my invention to provide a spring for furniture and the like which obviates the use of coil springs or webbing.

It is another object of my invention to provide a spring for furniture and the like which is cheap, easy of manufacture, and obviates the use of metal, if desired, and of a considerable amount of the padding usually employed in upholstered furniture.

It is a further object of my invention to provide a spring which will furnish the desired springing action all along its length, from the front to the rear thereof.

These and further objects and advantages of my invention will appear from a consideration of the following detailed description and accompanying drawing, in which:

Fig. 1 is a perspective view of an armchair with the seat cushion removed and having in the seat thereof several of my springs;

Fig. 2 is an enlarged vertical cross-section taken along line 2—2 of Fig. 1; and

Fig. 3 is an enlarged vertical cross-section of a modification of my invention.

Referring now to the accompanying drawing, 10 designates an armchair having the usual front rail 11, side rails 12, back rail 13 and legs 14. The usual seat cushion has been omitted from the chair 10 in Figure 1 the better to show the springs 15. Three springs 15 are provided in the seat of the chair 10 but it will be understood that any number of springs 15 may be used, they may be of any desired width, and they may also be employed in the back of the chair to provide spring action there if desired. The front rail 11 is provided with a ledge 16 on the inner side thereof, which ledge may be made integral with the front rail or may be a separate piece of wood or other suitable material secured to the rail 11 in any suitable manner.

Each spring 15 is preferably made of wood and consists of a rectangular spring leaf or slat

17 secured at its front end to the front rail 11 by a screw 18 or other suitable manner such as by glue, bolt or the like.

Below each leaf 17 is placed a rectangular 5 spring leaf 19, the front end of which is spaced below the front end of leaf 17 and rests on the ledge 16. The rear end of lower leaf 19 is secured to the rear end of upper leaf 17 as by a clamp 20, but these ends may be secured together by bolts, glue or any other desired manner. The rear ends of leaves 17 and 19, while secured together, are not secured or attached to the back rail 13 but are spaced therefrom so that said rear ends may move vertically. The 10 length of lower leaf 19 is such that when secured at its rear end to the rear end of leaf 17, it has to be bowed or bent so that the front end thereof will rest on ledge 16 and abut the inner side of front rail 11. In this manner a spring resilience 15 is provided for the pair of leaves 17 and 19.

It will be evident that with leaves 17 and 19 combined as shown a spring is provided which will yield and provide the necessary spring action 20 in the rear portion of the seat when sat upon. Leaves 17 and 19 are made sufficiently 25 stiff so that the rear ends thereof will not descend to the floor when the chair is sat upon. Further to insure this result, leaf 17 is preferably 30 made so that its thickness is progressively greater starting from the front and moving to the rear thereof, while the reverse is the situation with leaf 19; the front of leaf 19 is preferably 35 made thicker than the rear thereof. With such construction the resistance of the spring action is increased as the weight on the seat is increased.

If desired, leaves 17 may be alternated in their 40 attachment to the chair. For example, the first leaf 17 may be attached to the front rail 11 as explained above, and the adjoining leaf attached to the back rail 13 and having its other end free to move vertically. Then the next adjoining leaf 17 may be attached to the front rail 11 and 45 the next leaf to the back rail. This method of construction provides a springing action all along the surface where such springing action is desired.

To provide more positive spring action at the 50 front of the seat, I prefer to provide another pair of rectangular spring leaves 21 and 22 superposed above leaves 17 and 19. Leaf 21 is provided at its front end with a downwardly extending projection 23, and is made long enough so 55 that the front of projection 23 is approximate-

ly in the same vertical plane as the front of rail 11. Below leaf 21 is placed leaf 22, the rear end of which is secured to the rear end of leaf 21 and the rear ends of leaves 17 and 19, as by clamp 20, but none of these rear ends is secured to the back rail 13 and all are spaced therefrom so that they are free to move in a vertical plane.

The length of leaf 22 is such that when it is secured at its rear end to the rear end of leaf 21, it has to be bowed or bent so that the front end thereof is forced against the corner formed by the conjunction of projection 23 and leaf 21. Leaf 22 is preferably bowed in a downward direction so that the ends project upward as shown in Figure 2.

The combination of the leaves 21 and 22 provides a spring action in the front of the seat when sat upon, and the combination of all four leaves 17, 19, 21 and 22 provides a spring action all along the seat.

This spring action all along the seat may also be provided by using a plurality of upper pairs of leaves 21 and 22. For example, two pairs of such leaves may be used, one behind the other, the forward one attached at its rear end to the middle of leaf 17 and the rear one attached at its rear end to the rear end of leaf 17.

As shown in Figure 2, leaf 21 is preferably made progressively thicker at the rear end than at the front end thereof, while leaf 22 is preferably made progressively thicker at the front end than at the rear end thereof. This construction tends to increase the resistance of the spring action when the weight on the seat is increased.

The usual padding 24 for the seat is shown in Figure 2 and is attached to the front side and back rails of the chair in the regular manner, but this padding and its method of attachment to the chair rails form no part of my invention, except that when my springs are used, very little padding is necessary and no springs need be employed in the padding.

In Figure 3 I have shown a modification of the construction shown in Figure 2. The modification consists in the reversal of the arc of leaf 19. In the modified form of my invention, the rear springing action is furnished by a rectangular spring leaf 26 secured to the front rail 11 as shown in Figure 2 with regard to leaf 17 and secured at its rear to the rear of a rectangular bowed spring leaf 27 which is below it. The front end of leaf 27 abuts the two sides of the joint formed by the conjunction of the inner surfaces of leaf 26 and front rail 11. The arc of leaf 27 is downward as shown in Figure 3.

The front springing action in the modification is provided by a pair of spring leaves 28 and 29 superposed above leaves 26 and 27 but identical in construction and action with leaves 21 and 22 shown in Figure 2. In this modified construction, leaf 26 is preferably made progressively thicker in front than at the rear thereof while leaf 27 is progressively thicker at the rear than at the front thereof. The rear ends of leaves 26, 27, 28 and 29 are secured together but are spaced from and not secured or attached to the back rail 13 so that these rear ends are free to move in a vertical plane.

It will be understood that while I have shown the leaves of my spring as varying in thickness, all the leaves may be of the same thickness, or some leaves may have varying thicknesses and others not, without detracting from the advantages of my invention, and also that while I have shown my spring as rectangular and made of

wood, the spring may be of other shapes and made of metal or any other suitable material. In addition, the spring may be reversed so that all the front ends of the leaves thereof are spaced from the front of the chair and may move vertically, while one leaf of the spring is secured to the rear of the chair, so that the action of the pairs of leaves is reversed, but the final result will be the same. Moreover, my invention is not to be limited for use in chairs, but may be employed in sofas, beds and the like or in other articles where spring action is desired.

I do not wish to be limited to the specific construction shown in the drawing, as changes may be made therein without departing from the spirit of my invention. The drawing and description are to be considered as merely illustrative of the invention and not as limiting it, and the scope of the invention is to be ascertained by reference to the following claims.

I claim:

1. In an article to be made resilient, the combination of a framework and a plurality of pairs of superposed resilient members, one pair consisting of an upper resilient member secured at one end to said framework and having its other end spaced from the other side of the framework so that it may be moved and a lower resilient member below said upper resilient member having one end removably abutting the framework below the secured end of said upper resilient member and having its other end spaced from said framework and secured to the movable end of said upper resilient member so that it may move therewith, and another pair above said first mentioned pair of resilient members and consisting of an upper resilient member secured at one end to the upper resilient member of said first mentioned pair of resilient members and having its other end projecting above the secured end of the upper resilient member of the first mentioned pair of resilient members and a lower resilient member having one end removably abutting the projecting end of the upper resilient member of the second mentioned pair of resilient members and having its other end secured to the secured end of the upper resilient member of the second mentioned pair of resilient members.

2. In an article to be made resilient, the combination of a framework and a plurality of pairs of superposed leaf springs, one pair consisting of an upper leaf spring secured at one end to said framework and having its other end spaced from the other side of the framework so that it may be moved and a lower leaf spring below said upper leaf spring having one end removably abutting the framework below the secured end of said upper leaf spring and having its other end spaced from said framework and secured to the movable end of said upper leaf spring so that it may move therewith, and another pair of leaf springs above said first mentioned pair and consisting of an upper leaf spring secured at one end to the upper leaf spring of said first mentioned pair of leaf springs and having its other end projecting above the secured end of the upper leaf spring of the first mentioned pair of leaf springs and a lower leaf spring having one end removably abutting the projecting end of the upper leaf spring of the second mentioned pair of leaf springs.

3. In an article to be made resilient, the combination of a framework and two pairs of super-

posed leaf springs extending from one side of the framework to the other side thereof, the lower pair consisting of an upper leaf spring secured at one end to one side of the framework and having its other end spaced from the other side of the framework so that it may be moved and a lower leaf spring below said upper leaf spring having one end thereof removably abutting the side of the framework below the secured end of the upper leaf spring and having its other end spaced from the other side of said framework and secured to the movable end of said upper leaf spring so that it may move therewith, said upper pair of leaf springs above the first mentioned pair consisting of an upper leaf spring having one end thereof projecting above the secured end of the upper leaf spring of the lower pair of springs and having its other end secured to the movable ends of the lower pair of leaf springs.

4. The combination described in claim 2 wherein the lower resilient leaf spring of each pair of leaf springs is bowed.

5. In an article to be made resilient, the com-

bination of a framework, a projection on one side of the framework, and two pairs of superposed leaf springs, the lower pair consisting of an upper leaf spring secured at one end to the side of the framework above said projection and having its other end extending toward the other side of the framework but spaced therefrom so that it may be moved and a lower leaf spring below said upper leaf spring having one end thereof removably abutting said projection and the adjoining side of the framework and having its other end extending beneath the said upper leaf spring and secured to the movable end thereof so that it may move therewith, said upper pair of leaf springs above the first mentioned pair consisting of an upper leaf spring having one end thereof extending above the secured end of the upper leaf spring of the lower pair of springs and having a projection at the said end and having its other end secured to the movable ends of the lower pair of leaf springs and a lower leaf spring having one end thereof removably abutting the projection on the end of the upper leaf spring of the upper pair of leaf springs and having its other end secured to the movable ends of the other leaf springs.

JOSEPH N. WEIL.
